CHARLES E. LUCKE, OF NEW YORK, N. Y., ASSIGNOR TO WORTHINGTON PUMP AND MACHINERY CORPORATION, OF NEW YORK, N. Y., A CORPORATION OF VIRGINIA.

OIL-PUMPING SYSTEM.

Application filed March 16, 1926. Serial No. 95,160.

This invention relates to oil pumping systems and an object of the invention is to provide a system for lowering the viscosity of petroleum, in its crude state or its products, 5 to permit the use of standardized circulating pumps at maximum efficiency in pumping the oil from one place to another.

Owing to the variability of the viscosity of oils (petroleum, crude or its products), found 10 in different oil-producing sections of the country and also due to the fact that in some cases the oil does itself vary, difficulty has been experienced in the use of oil circulating pumps and particularly centrifugal pumps 15 for pumping the oil as viscosity of fluids pumped affects pump performance. When the viscosity is greater than a certain amount, the pump practically, or actually stops delivery because it does not properly fill. These 20 conditions necessitate a different design of pump for each oil of a particular viscosity, and to permit the use of standardized circulating pumps and to obtain the highest efficiency thereof, in pumping such oils it is 25 necessary to maintain a pre-determined low-value viscosity of the oil.

An object of the present invention is to provide a system for maintaining the desired low-value viscosity of the oil to be pumped, 30 which system will be relatively inexpensive in operation and permit the utilizing of the maximum amount of heat from the oil itself, in standardizing the viscosity, and will use a minimum amount of fuel in the heating of 35 the oil, but in cases where the prime mover of the pump generates heat, such as internal combustion engines, the invention comprehends the utilizing of the waste heat discharged from the exhaust of the engine for 40 heating the oil to lower its viscosity.

One form of the invention comprehends the provision, in an oil pumping system of a heater which initially heats the oil to provide the desired low-value viscosity prior to 45 the entrance of the oil into the pump and which system further embodies a heat exchanger through which the heated oil from the pump is forced and through which the oil on its travel to the pump, passes, thereby permitting the exchanging of the heat from the oil pumped from the pump to the oil going to the pump for lowering the viscosity of the oil and permitting a cutting out of the operation of the heater until the heat absorbed by

the incoming oil during its passage through 55 the heat exchanger is insufficient to lower the viscosity of the oil to the desired low value after which time the heater may be again brought into effective operation for heating the oil. 60

With these objects in view, the invention consists in various features of construction and combination of parts, which will be first described in connection with the accompanying drawings, showing an oil pumping system of the preferred form embodying the invention, and the features forming the invention will be specifically pointed out in the claims. 65

Figure 1 illustrates in a diagrammatic 70 manner the improved oil pumping system utilizing a heater and a heat exchanger in which the incoming oil is heated by the outgoing oil.

Figure 2 illustrates in a diagrammatic manner an improved oil pumping system utilizing an internal combustion engine the exhaust of which heats the incoming oil to 75 lower its viscosity.

Referring more particularly to the drawings the cold oil from the pipe line to the pump suction passes from the pipe 1 into the sinuously curved pipe 2 of the heat exchanger structure 3, and passes from the pipe 2 into the tubes 4 of the heater 5 through a suitable 80 pipe or conduit 6. When the system is first started the oil is heated in the heater 5 by heat supplied from an oil burner 7 of any 85 approved construction. The heat from the burner 7 and the number of tubes 4 are regulated to heat the oil sufficiently to lower its viscosity to a desired low value, and after 90 leaving the tubes 4 of the heater the oil passes into the suction of a circulating pump 8 from which it is discharged through the pipe 9 into the pipes 10 of the heat exchanger. The 95 heated oil passing through the pipes 10 of the heat exchanger 3, passes about the pipe 2 and the oil passing through the pipe 2 to the heater 5 and pump 8 is heated by the oil pumped from the pump through the pipe 10 of the heat exchanger. The oil passes from the pipes 10 into a suitable pipe line 11 through which it is conveyed to the desired 100 delivery point. 105

It will be apparent that the oil passing through the pipe 2 of the heat exchanger, will have its viscosity lowered, by heating, and

it will, therefore, be unnecessary to heat the oil in the heater 5 and for this reason any suitable means may be provided for controlling the operation of the burner 7. Control of the operation of the burner 7 may be had by a manually operated valve 12 or by a thermostatic control structure of any approved type as indicated at 13. If the operation of the burner 7 is manually controlled, it will be necessary, only to watch the operation of the pump 8, and when it fails to operate properly due to the raising of the viscosity of the oil by failure of proper heating in the heat exchanger, to open the supply of fuel to the burner 7 and permit heating of the oil in the heater 5 until such time as sufficient heat is exchanged in the heat exchanger 3 to again permit the cutting off of the heating of the heater 5.

With the exchanger 3 properly designed and arranged, the oil passing therethrough to the pump, will be very much heated without the expenditure and loss of any more heat than that which corresponds to radiation and such loss is made up by the heater 5 and it will be apparent that the system may work for relatively long periods without the generating of heat by the heater 5 and solely with the action of the exchanger, permitting the heater to be operated intermittently.

In the modified form of the invention illustrated in Figure 2 of the drawings, an internal combustion engine 20 of any approved design is illustrated as the prime mover for operating the circulating pump 21 and in this system the exhaust gases from the engine 20 pass from the exhaust pipe 22 into a heat exchanger 23. The incoming oil from the pipe line of the pump suction passes through the sinuous pipe 24 of the heat exchanger and is heated by the outgoing exhaust gases from the engine. The exhaust gases from the engine are distributed to the atmosphere from the outlet 25 of the heat exchanger.

From the foregoing description taken in connection with the accompanying drawings, it will be apparent that with an oil pumping system constructed in either the preferred or modified form, oil, regardless of its normal viscosity, may be heated to a desired low-value viscosity and by heating different oils to different degrees they may be brought to substantially the same viscosity which will permit the effective and efficient

operation of a standard circulating pump in the pumping of the oil.

While this invention is particularly adapted for use with centrifugal pumps, it is to be understood that it is also adaptable for use with rotary or displacement pumps.

It will be understood that the invention is not to be limited to the specific construction or arrangement of parts shown but that these may be modified widely within the invention defined by the claims.

What I claim is:

1. In an oil pumping system, the combination with a pump, of means for regulating the viscosity of oil flowing to the pump suction to a pre-determined value including a heat exchanger through which the oil passes, said heat exchanger utilizing the oil during one part of its passage through the system as the heating medium for heating the oil.

2. In an oil pumping system, the combination with a pump, of means for maintaining a pre-determined viscosity of the oil passing to the pump including, a heater, and a heat exchanger through which the oil passes to the heater and through which the oil is pumped from the pump delivery.

3. In an oil pumping system, the combination with a pump, of means for maintaining a pre-determined viscosity of the oil passing to the pump including a heater, a heat exchanger through which the oil passes to the heater and through which the oil is pumped from the pump delivery, and means for controlling operation of the heater.

4. In an oil pumping system, the combination with a centrifugal pump, of means for maintaining a pre-determined viscosity of the oil passing to the pump including a heater, a heat exchanger through which the oil passes to the heater and through which the oil is pumped from the pump delivery, and control means operated by the temperature of the oil passing to the heater for controlling operation of the heater.

5. In an oil pumping system, the combination with a pump, of means for regulating the viscosity of oil flowing to the pump suction, including a heat exchanger through which the oil passes to the pump suction and through which the oil is pumped from the pump delivery, said heat exchanger utilizing the oil during one part of its passage through the system as the heating medium.

In testimony whereof I affix my signature.

CHARLES E. LUCKE.
